(57) **CLAIM**

The ornamental design for a work vehicle body, as shown and described.

DESCRIPTION

FIG. 1 is a top, rear, left perspective view of a work vehicle body showing my new design shown with example work vehicle environment;

FIG. 2 is a top, rear, left perspective view thereof shown with example engine cover environment;

FIG. 3 is a left side elevational view thereof;

FIG. 4 is a right side elevational view thereof;

FIG. 5 is a top plan view thereof;

FIG. 6 is a rear end view thereof;

FIG. 7 is a front end view thereof;

FIG. 8 is a bottom plan view thereof; and,

FIG. 9 is a top, rear, right perspective view of work vehicle body according to another embodiment of my new design shown with example engine cover environment, the various views thereof are mirror images of the views shown in FIGS. 3-8.

The broken line representations in the figures, including the broken line example work vehicle and engine cover environment, show unclaimed environment or boundaries, and thus form no part of the claimed design.

The nature of this product is an exterior body for a vehicle, such as a work vehicle used in the construction and forestry industries, for example an engine cover or portion thereof for a wheeled loader.
